(57) CLAIM

The ornamental design for a handle for edge-replaceable saw, as shown and described.

DESCRIPTION

FIG. 1 is a perspective view of a handle for edge-replaceable saw;

FIG. 2 is a front view thereof;

FIG. 3 is a top view thereof;

FIG. 4 is a back view thereof;

FIG. 5 is a bottom view thereof;

FIG. 6 is a right side view thereof;

FIG. 7 is a left side view thereof;

FIG. 8 is a cross section view taken along line 8—8 of FIG. 2; and,

FIG. 9 is a front view thereof, wherein the broken line showing of the blade is for illustrative purposes only and forms no part of the claimed design.
